United States Patent Office

Des. 210,152
Patented Feb. 13, 1968

210,152

PADDLE LOCK

John V. Pastva, Jr., Parma Heights, Ohio, assignor to
The Eastern Company, Cleveland, Ohio, a corporation of Connecticut

Filed Sept. 2, 1966, Ser. No. 3,706

Term of patent 14 years

(Cl. D50—5)

FIG. 5

FIG. 1 is a front elevational view of a paddle lock embodying my new design;

FIG. 2 is a side elevational view of the righthand side of the paddle lock shown in FIG. 1;

FIG. 3 is a top plan view of the paddle lock shown in FIG. 1;

FIG. 4 is a side elevational view of the left-side of the paddle lock shown in FIG. 1; and

FIG. 5 is a rear elevational view of the paddle lock.

I claim:

The ornamental design for a paddle lock, substantially as shown.
